[57] CLAIM

The ornamental design for a cosmetics applicator, as shown and described.

DESCRIPTION

FIG. 1 is a front and left side perspective view of a cosmetics applicator showing my new design, in which the cover is on; FIG. 2 is an exploded version of FIG. 1 in which the top is off;

FIG. 3 is a right side elevational of my design, the left side being a mirror image;

FIG. 4 is a rear view thereof; and,

FIG. 5 is a bottom plan view thereof.
